UNITED STATES PATENT OFFICE.

MATTHEW I. VINOBERATZ, OF HIBBING, MINNESOTA.

DESIGN FOR A CLOCK-CASE AND BASE ATTACHMENT FOR ARTICLES OF FURNITURE.

52,516.

Specification for Design.

Patented Oct. 1, 1918.

Application filed January 2, 1918. Serial No. 210,096. Term of patent 7 years.

To all whom it may concern:

Be it known that I, MATTHEW I. VINOBERATZ, a citizen of the United States, residing at Hibbing, county of St. Louis, and State of Minnesota, have invented a new, original, and ornamental Design for a Clock-Case and Base Attachment for Articles of Furniture, of which the following is a specification, reference being had to the accompanying drawing, forming a part thereof.

In the drawings:—

Figure 1 is a perspective view of the new, original, and ornamental design for a clock case and base attachment showing the article of furniture in dotted lines.

Fig. 2 is a plan view of the new, original, and ornamental design for a clock case and base attachment.

Fig. 3 is an end view.

In Figs. 2 and 3 the showing of the article of furniture is omitted.

I claim:—

The ornamental design for a clock case and base attachment for articles of furniture, substantially as shown.

Applicant's name is signed to this application in the presence of two witnesses.

MATTHEW I. VINOBERATZ.
